UNITED STATES PATENT OFFICE.

CHARLES A. HARBAUGH, OF LINWOOD, KANSAS.

EXPLOSIVE LOCK.

1,390,704.

Specification of Letters Patent. Patented Sept. 13, 1921.

Application filed May 25, 1920. Serial No. 384,175.

To all whom it may concern:

Be it known that I, CHARLES A. HARBAUGH, a citizen of the United States, residing at Linwood, in the county of Leavenworth, State of Kansas, have invented a new and useful Explosive Lock; and I do hereby declare the following to be a full, clear, and exact description of the invention, such as will enable others skilled in the art to which it appertains to make and use the same.

The invention relates to locks, safes, vaults and the like and has for its object to provide an explosive device which will explode when the locks are tampered with by unauthorized persons, the explosive charge being sufficient to act as an alarm and at the same time may be so regulated as to so injure the intruder so that he can be easily apprehended.

20 A further object is to provide a lock having in connection therewith a hand grenade preferably of the Mills type and so connected to the lock that when the lock is forced open by an unauthorized person the 25 firing pin of the grenade will be released and the grenade allowed to explode. Also to provide means whereby the firing pin may be held against movement when the lock is being opened by an authorized person.

30 With the above and other objects in view the invention resides in the combination and arrangement of parts as hereinafter set shown in the drawings, described and claimed, it being understood that changes in 35 the precise embodiment of the invention may be made within the scope of what is claimed without departing from the spirit of the invention.

In the drawings:—

40 Figure 1 is a sectional view through a conventional form of lock showing the invention applied thereto.

Fig. 2 is an enlarged sectional view showing the lock shackle arm which engages and 45 holds the grenade firing pin.

Fig. 3 is a perspective view of a portion of the grenade showing the firing pin.

Fig. 4 is a detail sectional view taken on line 4—4 of Fig. 1 looking in the direction 50 of the arrows.

Fig. 5 is a side elevation of the lock body showing key aperture, which may be concealed and in which aperture a key may be placed for holding the firing pin against 55 movement when authorized persons are operating the lock.

Referring to the drawings, the numeral 1 designates the lock body and 2 the shackle thereof. Shackle 2 has its arm 3 rotatably mounted in bearings 4 of the lock body so 60 that when the detents 5 which engage the arm 3 are thrown out of engagement with the arm 3, the shackle may be pivoted around on said arm. The lower detent 6 has one of its ends disposed in an aperture 7 in the arm 65 3 and in engagement with an annular groove 8 of the firing pin 9. Detent 6 holding the firing pin against the action of the spring 10 until the lock is forced open by an authorized person or by a skeleton key. The 70 firing pin is normally held in its outer position and when released fires the grenade 11, therefore it will be seen that when the detents 5 and 6 are moved out of engagement with the arm 3, either by rotation of the key 75 12 or by forcing the lock that the upper end 13 of the firing pin will be released from the recess 14 and will move downwardly under the impulse of the spring 10 and explode the 80 grenade.

The firing pin 9 is slidably mounted in a bushing 15 which is threaded in the bore 16 of the body of the lock, thereby allowing the removal of the upper end of the firing pin from engagement with the lower detent 6 85 this being accomplished by a downward pull on the grenade and by screwing outwardly on the bushing 15 until it is out of the bore 16, then the firing pin can be moved outwardly until it clears the end of the detent 6 90 and then moved downwardly and out of engagement with the lock. However when an authorized person desires to open the lock, said person will place a key 17 in a concealed aperture 18. The inner end of the key will 95 engage the notch 19 on the firing pin 9 and hold the firing pin against downward movement so that the detents 5 and 6, may be moved out of engagement with the arm 3 of the shackle 2 without danger of releasing the 100 firing pin and consequent explosion of the grenade. Concealed pocket 18 may be concealed in any suitable manner however a pivoted cover 19^a is shown for purposes of illustration.

105 From the above it will be seen that a lock attachment is provided, which attachment will when it explodes, not only give an alarm, but will injure the unauthorized intruder so that he may be easily apprehended. 110 It being the object to inflict as small amount of injury as possible to the intruder and at

the same time to so regulate the charge that it will do a minimum amount of damage to the surrounding property.

The invention having been set forth what is claimed as new and useful is:—

The combination with a lock having a lock bolt disposed therein, of an explosive device therefor, said explosive device comprising a casing having a spring actuated firing pin 10 therein, said firing pin extending through the lock casing and having its end axially disposed in a recess in the end of the lock bolt, a recess carried by said firing pin and registering with an aperture in the end of 15 the lock bolt, said recess and aperture being

in alinement with a detent carried by the lock and held, said firing pin being held against the action of its spring by the detent and released by said detent, and means whereby spring actuated firing pin may be 20 held against movement under the influence of its spring independent of the detent.

In testimony whereof I have signed my name to this specification in the presence of two subscribing witnesses.

CHARLES A. HARBAUGH.
